UNITED STATES PATENT OFFICE.

WILLIAM THOMAS MILWARD, OF HANDSWORTH, ENGLAND.

DEVICE FOR HOLDING DOWN MATS, CARPETS, OR THE LIKE.

No, 910,940.

Specification of Letters Patent.

Patented Jan. 26, 1909.

Application filed August 7, 1908. Serial No. 447,481.

To all whom it may concern:

Be it known that I, WILLIAM THOMAS MILWARD, a subject of the King of Great Britain, residing at 14 Holyhead road, Handsworth, in the county of Stafford, England, gentleman, have invented a new and useful Improved Device for Holding Down Mats, Carpets, or the Like; and I do hereby declare the following to be a full, clear, and

exact description of the same.

This invention comprises an improved device for holding down mats, carpets, or the like, and has for its object to provide an improved spring pressed flap or holder applicable to a door jamb or like part for exerting pressure on the edges of a carpet or the like to keep the same down in proper place, without presenting surfaces likely to be in the way.

The device consists of a spring flap or holder which may be of wire or plate form hinged to a securing plate, with a spring about its hinge and also with means such as a hook for retaining the plate or tongue in inoperative position when desired.

On the drawings: Figure 1. shows a perspective view of a door with the mat holders in position holding down the mat. Fig. 2. shows a front view of the device with the holder part or flap extended. Fig. 3. shows a vertical section on Fig. 2 and Fig. 4. shows a section of a modification in which the pivoted hook in the other figures is replaced by a spring clip for securing the holder or flap in the disengaged position as shown by the dotted lines.

In the drawings the flap F is shown constructed of stout wire which is bent in the form of a "trapezium". The ends of the wire practically meet on the short side and form convenient parts for the hinge. The hinging of the flap is effected by springing the ends of the wire into the curled over portion B of the attachment plate A which is screwed to the jamb of the door, or other suitable part as required. A spring S is arranged around the hinged joint bearing at one end on the flap and at the other on

the plate A and so arranged as to urge the flap downwards. As will be understood from reference to the drawings the movement of the flap toward the attachment plate is against the action of the spring S. Thus when the device is arranged in position for use such as at Fig. 1 or otherwise to suit particular requirements, the flap F is exerting pressure down onto the mat M or the like arranged beneath it, thus keeping it in place. The arrangement of the spring flap in this way allows a strong durable spring being used. At the top of the attachment plate A is hinged a hook H which holds up the flap out of engagement when it is required to move the mat. As shown in Fig. 4, this hook may be replaced by a spring clip K formed out of a piece of bent metal at the top of the plate A.

What I claim then is:

1. In a device for holding down door mats and the like, a metal plate, a hinged flap at the foot of the plate, and a spring urging said flap away from said plate, and flap retaining means on said plate, substantially as described.

2. In a device for holding down door mats, and the like, a metal plate, a hinged flap at the foot of the plate, and a spring urging said flap away from said plate and a hinged hook at the top of said plate, said plate being capable of being secured to a support and having the top extremity tongued, said tongue being bent over to form a bearing for said hook, said plate being turned over at the base to form a bearing and hinge for said flap, said flap being formed of bent wire in a suitable form and urged outward by said coiled wire spring wound round said flap and inside said bottom hinge substantially as described.

In testimony whereof, I have signed my name to this specification in the presence of two subscribing witnesses.

WILLIAM THOMAS MILWARD.
